UNITED STATES PATENT OFFICE.

FRANK H. BANCROFT, OF GARDNER, MASSACHUSETTS, ASSIGNOR OF ONE-HALF TO HENRY M. RICH, OF SAME PLACE.

PRESS FOR BENDING WOOD.

SPECIFICATION forming part of Letters Patent No. 679,287, dated July 30, 1901.

Application filed April 25, 1900. Serial No. 14,249. (No model.)

To all whom it may concern:

Be it known that I, FRANK H. BANCROFT, a citizen of the United States, and a resident of Gardner, in the county of Worcester and Commonwealth of Massachusetts, have invented certain new and useful Improvements in Presses for Bending Wood, of which the following is a specification, reference being had to the accompanying drawings, forming a part 10 of the same, in which—

Figure 1 represents a front view of a press for bending wood embodying my invention. Fig. 2 is a side elevation of the same. Fig. 3 is a view of one end of the bar P and a portion 15 of one of the rack-bars. Fig. 4 is an end view, partly in section, of the forms N and X.

Similar reference-letters refer to similar parts in the different views.

My invention relates to a press for bending 20 wood, having fixed and reciprocating bars whose opposing surfaces are curved or so shaped as to bend pieces of wood placed between them; and it consists in certain improvements in the press for bending wood 25 forming the subject of my application for Letters Patent of the United States, Serial No. 735,452, filed November 1, 1899.

My invention has for its object to provide 30 means for supporting the convex side of the wood during the process of bending in order to cause the bending strain to be more uniformly distributed; and it consists in the novel features as hereinafter described, and set forth in the annexed claims.

35 Referring to the drawings, A denotes the base of the machine, supporting a hydraulic cylinder B, having a plunger C. Mounted upon the base A are a pair of upright posts D, connected together at their top by a cross- 40 head E, constituting the upper form and consisting of a hollow shell having its under side E' presenting a convex surface and adapted to coöperate with a hollow movable form F, capable of vertically sliding upon the upright 45 posts D and having a corresponding concave upper surface F', the forms E and F constituting pressing members between which the articles to be bent are placed.

Below the form F is a similar form G, having 50 a concave surface G', adapted to coöperate with a convex surface F² on the under

side of the form F, the pressing-surfaces E' and F' and F² and G' being adapted to bend articles of wood—such, for example, as chair-legs—so their curvature will correspond with 55 the curved pressing-surfaces, the pressing being accomplished by carrying the movable forms F and G upwardly by the action of the plunger C in the manner common in machines of this class and as set forth in my 60 application aforesaid, Serial No. 735,452. In order to cause the central portion of the articles H to be bent to closely hug against the convex surfaces against which they are pressed in the operation of bending by the 65 upward motion of the movable forms, I place beneath the articles H a curved spring-plate I, having its ends resting upon the concave surface of the movable form and its convex surface bearing against the articles H and 70 crowding them into close contact with the convex pressing-surface. In the accompanying drawings the articles H between the forms E and F are represented as having been pressed into their proper curved shape and 75 held by fastening the movable form F to the upright posts D by means of the set-screws J. The forms F and G are represented in the drawings as separated in position to receive the articles H to be bent, which are supported upon the brackets K, with their upper 80 surfaces against the central portion of the form F. Beneath the articles H, between the forms F and G, is placed a spring-plate I, consisting of a curved elastic sheet of metal, with 85 its ends resting upon the concave surface of the form G and with its central portion arranged to press against the under side of the articles H as the form G is raised. As the articles H are bent the elastic sheet of metal I is 90 crowded downward and curved in the opposite direction and pressed against the concave surface G' in the same position as the spring-plate between the forms E and F. The pressure of the spring-plate I causes the articles to be 95 bent to be held closely against the central portion of the convex surface of the form upon which they are bent and applies a pressure to the opposite side of the bent articles, thereby preventing the splintering of the 100 wood on its convex side and causing the bending strain to be more equally distributed

throughout the entire width of the pressing-surface. Below the form G is shown a curved form M, which bears against the under surface of the form G and is provided on its under surface with a convex surface M', fitting the concave surface N' of the form N and constituting the pressing-surfaces, between which the articles O are bent. The articles O when placed between the forms

- 10 are supported between ribs O² upon a thin sheet-metal apron O', which rests upon the form N when in its lowest position. The concave surface N' of the form N is provided at its central portion with a recess N³, in which
- 15 is placed a bar P, normally lying in the recess N³ with its ends projecting over the vertical bars Q Q, which are capable of a vertical sliding motion and are provided with rack-teeth R, engaged by pinions (not shown)
- 20 on the shafts S S.

The shafts S carry upon their ends hand-wheels T, by which the shafts S are rotated in order to raise and lower the bars Q Q. The bars Q Q are provided upon their upper ends

- 25 with a tongue Q', adapted to engage a groove P' in the under side of the bar P, so that when the rack-bars Q are raised the bar P will be lifted and carried against the under side of the apron O' with sufficient pressure
- 30 to hold the articles O firmly against the convex surface M', and the hand-wheels T are locked in position by means of a cam U, provided with a lever-handle V, by which the rim of the hand-wheel is clamped between
- 35 the cam U and the bearing-surface W. The form N is then moved up by the plunger C until the bar P is received into the recess N³ and the pieces O bent to conform to the curved surface of the forms M and N. The lower
- 40 form X is likewise provided with a recess Y, and the rack-bars Q Q are lowered and a bar placed in the recess Y and raised to hold the articles while they are being bent between the forms G and X. The bar P is preferably
- 45 slightly curved and elastic, so that as it is raised by the engagement of its ends by the vertically-sliding racks Q Q its central section is first carried into contact with the articles with the apron O', and as pressure is
- 50 applied to the ends of the bar it becomes

straightened, causing the pressure exerted by the center of the bar to be fully equal to that exerted by its ends. The movable forms slide loosely on the upright posts D and a slight tipping of the forms is permitted in 55 order to accommodate articles which are larger at one end than the other, and the ways in the form X and N are larger in cross-section than the vertically-sliding racks in order to provide for their free movement. I 60 employ the pressure-bar P between the lower forms or the forms below the form M, and above the form M, I employ spring-plates, such as I and L.

What I claim as my invention, and desire 65 to secure by Letters Patent, is—

1. The combination with a pair of pressing members, adapted to bend the articles pressed between them, of means for applying a pressure to the center of the articles to be bent 70 and consisting of an elastic curved plate having its ends bearing against one of the pressing members and its convex side applied to hold the articles against the other pressing member, substantially as described. 75

2. The combination of a pair of forms provided with opposing convex and concave pressing-surfaces, of a curved elastic plate with its ends resting on the concave surface, of one of said forms and with its convex surface adapted to hold the articles to be pressed against the convex surface of the other form, substantially as described. 80

3. The combination of pressing members provided with corresponding convex and concave surfaces, of a bar extending across and between said pressing members, rack-bars sliding in vertical ways and engaging said pressing-bar to carry it into contact with the articles to be pressed and hold them in contact with one of the pressing members, substantially as described. 85 90

In testimony whereof I have signed my name to this specification, in presence of two subscribing witnesses, this the 14th day of April, 1900. 95

FRANK H. BANCROFT.
